Inventor:

John Chase.

UNITED STATES PATENT OFFICE.

JOHN CHASE, OF FARMINGTON, PENNSYLVANIA.

IMPROVEMENT IN HARROWS.

Specification forming part of Letters Patent No. **84,342**, dated November 24, 1868.

To all whom it may concern:

Be it known that I, JOHN CHASE, of the town of Farmington, county of Warren, and State of Pennsylvania, have invented an Improved Form of Harrow; and I do hereby declare that the following is a full, clear, and exact description of the same, reference being had to the annexed drawing, making a part of this specification, and to the letters of reference marked thereon.

The nature of my invention consists in the construction of an implement which shall operate over obstructions and uneven surfaces more effectively than any harrow now in use.

To enable others to make and use my invention, I will proceed to describe its construction.

The harrow is composed of four parts, united by means of hook-and-eye joints, the hooks being placed on the leading part, and the eyes on the part following. Instead of hooks and eyes, clevises may be used for joints.

The materials to be used are wooden scantling for the frame, (I prefer oak, two and a half by three inches,) into which steel teeth are inserted at suitable intervals, and forged or cast iron joints.

B, the leader, is constructed in the form of the ordinary "A-drag," widened, and a central stick, *c*, inserted.

D, the central follower, is of the simplest form of the A-drag, and is attached to the central stick *c* of the leader.

E E, the right and the left flanks, are in form like the common "square drag," of such proportions that one side in each shall be equal in dimension to the distances between the rear ends of the leader *m m* and those of the central follower *n n*. Other forms of drags may be used for the "follower" or "flanks."

In the construction of the several parts the scantling may be halved together, or framed by means of tenons and mortises, beveled where necessary, as in the A-drags.

What I claim as new, and desire to secure by Letters Patent, (all else being disclaimed as old,) is—

The arrangement and combination of the several parts B D E E, substantially as herein shown and described.

JOHN CHASE.
